HARRY JONES, OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

MANHOLE FRAME AND COVER.

1,191,432.

Specification of Letters Patent. Patented July 18, 1916.

Application filed April 24, 1915. Serial No. 23,735.

To all whom it may concern:

Be it known that I, HARRY JONES, a citizen of the United States, and a resident of Suffern, in the county of Rockland and State of New York, have made and invented 5 certain new and useful Improvements in Manhole Frames and Covers, of which the following is a specification.

This invention relates to manhole frames 10 and covers, the object being to provide a construction embodying top and supplemental covers, which when in their seated position, prevent the egress of a liquid therethrough.

15 A further object is to provide a manhole frame with top and supplemental covers, so arranged that a liquid-tight construction is provided and of such design that the top cover may be removed without affecting the 20 liquid-tight juncture between the supplemental cover and a manhole frame.

Other objects and advantages will appear 25 as the description proceeds, wherein it is to be understood that changes in the precise embodiment of the invention can be made within the scope of what is claimed, without departing from the spirit of the invention.

The preferred embodiment of my invention 30 is disclosed in the accompanying drawings, wherein:—

Figure 1 is a view in side section of a manhole frame and covers embodying the characteristic features of my invention; Fig. 2 is a similar view with the covers removed 35 and with the view point shifted through 90°; Fig. 3 is a cross-sectional view taken on the line 3—3 of Fig. 1.

Referring to the several views, wherein 40 corresponding parts are indicated by similar numerals, a manhole frame 4, is provided at its upper extremity with the inwardly projecting ledge 5 defining a continuous recess 6 into which the top cover 7 is adapted to seat.

45 The side walls of the frame are provided with the continuous and inwardly protruding flange 8, the innermost extremity of which is projected upwardly to form the upstanding lip 9. A supplemental cover 10 is 50 adapted to rest down upon the said lip 9 and is formed with the spaced flanges 11, between which is located a gasket 12. The supplemental cover is thus adapted to rest upon the flange 8 with the gasket 12 in contact with the upstanding lip 9 whereby a

liquid-tight juncture therebetween is effected, preventing the egress of a liquid through the manhole frame.

The manhole frame 4 is provided with the spaced lugs 13, which are mounted below the flange 8, and arranged in superposed pairs so as to receive the extremities of the cross bar 14 therein, whereby the same may act in the capacity of a strut upon which a pressure may be exerted tending to draw the top and supplemental covers into their seated positions. The top cover 7 is provided with the stepped opening 15 for the reception of a pocket member 16. The pocket member 16 is formed with the opening 17 in the bottom wall, through which extends a bolt 18. The lower extremity of the bolt 18 is threaded as at 19, so as to engage the threaded opening 20 formed in the cross bar 14, so that, while the bolt may be entirely removed from the cross bar, it is adjustably secured thereto, and through the intervention of the wrench engageable head 21 and compression spring 22, is adapted to exert a downwardly directed force upon the supplemental cover 10, so as to resiliently hold the same in its seated and liquid-tight position. The bolt head 21 is positioned intermediate the ends of the shank 7, and the portion of the bolt 23 which extends thereabove is threaded and adapted to be engaged by the securing nut 24. The portion 23 of the bolt shank extends through the opening 17 in the pocket member, whereby the securing nut 24 is adapted to press down upon the pocket member and thus draw the top cover 7 into its seated position and firmly hold the same, so located.

The pocket member is provided with the detachable plug 25 which prevents the malicious removal of the covers and also maintains the interior of the pocket member free from sediment. The arrangement of the holding means, whereby the top and supplemental covers are held in their seated positions allows the top cover to be removed without disturbing the supplemental cover and also provides that either cover may be used independently of the other. A single bolt and cross rod is adapted to securely anchor both the covers in their seated positions, whereby a liquid-tight construction is effected, preventing the passage of a liquid through the manhole frame, even after the top cover has been removed.

In placing the various covers in position, the cross rod is first inserted in place, as disclosed in Fig. 1, with the extremities thereof resting between the lugs 13. The supplemental cover 10 is then placed upon and supported by the flange 8, and is drawn to its seated position by placing the bolt 18 through the compression spring 22 and forcibly rotating the bolt head 21, whereby the lower extremity of the compression spring will bear down upon the supplemental cover 8 and hold the same firmly in its seated and liquid-tight position. The top cover is then placed within the recess 6 and the securing nut 24 positioned upon the upper extremity of the bolt and tightened, whereby the covers will be firmly held in place and so maintained. The jars and shocks the top cover 7 will necessarily receive in service, will not be transmitted down to nor affect the liquid-tight juncture of the supplemental cover 10.

Having thus fully described my invention, what I claim is:—

- 25 1. A construction of the class described, comprising a manhole frame, top and supplemental covers therefor, said covers opening in an upward direction, and means engaging the said frame below the supplemental cover and independently engaging said top and supplemental covers and adapted to exert independently adjustable downward and seating forces upon the said covers.
- 30 2. A construction of the class described comprising a manhole frame, upwardly opening top and supplemental covers therefor, a detachable cross-bar engaging the frame below the said supplemental cover, a bolt member adjustably engaging said cross-bar and provided with a head above said supplemental cover, a resilient member interposed between said supplemental cover and head, adapted to exert a downward force upon the former, and means engaging the upper extremity of said bolt member and the top cover adapted to exert a downward force thereon.
- 35 3. A construction of the class described comprising a manhole frame, upwardly opening top and supplemental covers therefor, a detachable cross-bar engaging the said frame, a bolt member adjustably engaging said detachable cross-bar, means associated with said bolt member adapted to exert an independently adjustable downward force upon said supplemental cover, and means engaging said bolt member adapted to exert

an independently adjustable downward force upon said top cover.

4. An apparatus of the class described comprising a manhole frame, top and supplemental covers therefor, a member carried by said frame, a bolt threadedly engaging said member and provided with a head thereon, a resilient member interposed between said head and said supplemental cover, adapted to exert a downwardly seating force upon the latter, and means engaging the upper extremity of said bolt and said top cover adapted to exert a downwardly seating force thereon.

5. An apparatus of the class described, comprising a manhole frame provided with an upper ledge adapted to receive a top cover thereon, a top cover adapted to seat upon said ledge, an inwardly protruding flange carried by said frame, a supplemental cover adapted to seat thereon and effect a liquid-tight juncture therewith, a cross bar detachably engaging said frame below said inwardly protruding flange, and a bolt provided with threaded extremities and a head thereintermediate, the lower extremity of said bolt threadedly engaging said cross bar, resilient means interposed between the supplemental cover and bolt head adapted to exert a seating force upon said supplemental cover, and means carried by said top cover receiving the upper extremity of said bolt therein, and a securing nut engaging the protruding upper extremity of said bolt adapted to exert a downwardly seating force upon said top cover.

6. A manhole frame provided with an inwardly protruding flange with an upwardly extending peripheral lip, a supplemental cover with spaced downwardly projecting flanges, a gasket located between said flanges and adapted to contact with the flange lip of the manhole frame, a member carried by said frame, a bolt threadedly engaging said member and provided with a head thereon, a resilient member interposed between said head and supplemental cover adapted to exert a seating force upon the latter, a top cover and means engaging the upper extremity of said bolt and said top cover adapted to exert a seating force upon the latter.

Signed at Suffern in the county of Rockland and State of New York.

HARRY JONES.
